UNITED STATES PATENT OFFICE

HENRY L. ELLIOTT, OF CLAYSVILLE, PENNSYLVANIA, ASSIGNOR OF ONE-THIRD TO
THOMAS W. HENDERSON, OF WASHINGTON, PENNSYLVANIA

PULVERIZED FUEL CARBURETOR

Application filed February 19, 1929. Serial No. 341,100.

My invention relates to certain new and useful improvements in apparatus for carbureting air with pulverized fuel, namely pulverized coal and the like, for use in internal combustion engines, furnaces, or any other heating or power apparatus used for either domestic or industrial purposes.

Important objects of the invention are to provide an apparatus of the character described which will carburet air with pulverized material to render the latter highly combustible and provide a most efficient and economical pulverulent fuel for any purpose; which embodies novel means for storing the material prior to carburetion and for conveying the same subsequent thereto; and which includes an agitator element for leveling the powdered material, and a condenser for preventing spontaneous combustion and otherwise promoting the efficiency of the fuel.

Further objects of the invention are to provide a device of the class stated which is simple in its construction and arrangement, durable and efficient in its use, compact, positive in its action, and comparatively inexpensive to manufacture, maintain and operate.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings wherein like numerals of reference designate corresponding parts throughout the several views:

Figure 1 is a vertical cross sectional view of a fuel carburetor constructed in accordance with the invention.

Figure 2 is a top plan view thereof.

Referring in detail to the drawings 1 denotes a hopper or tank for housing the pulverized material. The tank 1 includes a rounded top 2, and a lower end portion 3 which tapers or converges toward the fuel outlet opening 4 provided in the lower end

thereof. The tank 1 is mounted in a supporting frame 5 of any suitable construction.

The tank top 2 is formed with an entrance opening 6 through which the pulverized material is placed in the tank 1. The entrance opening 6 is provided with a suitable removable cover 7.

An agitator 8 is suspended in the tank 1 and is fixed to the lower end of a square, vertically disposed shaft 9. The latter projects through the tank top 2, and is mounted for rotatable and longitudinal movement in the pair of bearings 10, 11, and in the bearing 12. The pair of bearings 10 and 11 are joined together by a yoke 13, which, together with the former, is fixed to the outer side of the tank top 2. The bearing 12 is disposed inside of the tank 1 and is fixed in position by a pair of bearing brackets 14 and 15, which are respectively fixed to the top and side wall of the tank 1.

The agitator shaft 9 carries a worm wheel 16, which is positioned in the yoke 13 intermediate of the pair of bearings 10 and 11. The shaft 9 extends through a square opening formed in the worm wheel 16, whereby the former rotates with the latter while being longitudinally shiftable therein. The worm wheel 16 meshes with the worm 17, which is fixed to the shaft of the driving motor 18. The latter is secured in position on the tank top 2.

The agitator is substantially propeller shaped, and is turned in such direction that its rotation will cause it to position and maintain itself on the top of the pulverized material in the tank 1. The purpose of the agitator 8 is to maintain the top of the pulverized material constantly leveled, and at the same time impart sufficient agitation and vibration to the housed pulverized material to prevent potential stagnation thereof during the operation of the device. The natural consistence of the pulverized material causes it to flow freely, and it is seldom that its flow is ever suspended through absolute inertness.

As the agitator 8 always functions on the top of the pulverized material in the tank 1, the variations of its positions are permitted by the longitudinal vertical movement of

the shaft 9 in its bearings 10, 11 and 12, and in the worm wheel 16. The vertical movement of the agitator shaft 9, however, is limited by a pair of stop collars 19 and 20. The collar 19 is fixed to the outer end of the shaft 9 and limits its downward movement, while the collar 20 is fixed adjacent to the lower end thereof and limits its upward movement.

A casing 21, providing a mixing chamber 22, is fixed to and below the lower tank portion 3. The outlet opening 4 establishes communication between the tank 1 and the mixing chamber 22, and is provided with a horizontally adjustable plate valve 23 for regulating its opening area to control the passage of the pulverized material from the tank 1 to the mixing chamber 22 to suit conditions required. A removable screen 24 is mounted to extend horizontally at the top of the mixing chamber 22 against the lower end of the outlet opening 4 in the tank 1.

A cylindrical brush 25 is fixed to the shaft 26, of an air motor 27, and is disposed horizontally in the mixing chamber 22. The periphery of the brush 25 brushes the under side of the screen 24 at all times, but is spaced from the bottom of the mixing chamber 22. The function of the brush 25 is to prevent clogging of the screen 24 and to maintain a constant, uniform flow of pulverized material therethrough during the operation of the device as hereinafter described.

The brush 25 is driven by the air motor 27 which receives its air supply from a compressed air reservoir 28 associated with an air compressor 29. An air supply conduit 30, provided with a suitable regulating valve 31, establishes communication between the air reservoir 28 and the air motor 27. The air is exhausted and passes from the air motor 27 to the mixing chamber 22 through the interconnected conduit 27'.

The tank top 2 is provided with an air dome 32, which communicates at its lower end with the tank 1. An air conduit 33 establishes communication between the air dome 32 and the air compressor 29. The air dome 32 is provided with a removable screen 34, which is disposed below the connection of the air conduit 33 to prevent entrance of any pulverized material to the conduit 33.

A condenser element 35, operated by any suitable means, is fixedly mounted in the tank 1 adjacent to the top thereof. The condenser element 35 is provided for condensing moisture or dehydrating the stored air and pulverized material to minimize loss of desired volatile properties of the latter. The condenser element 35 is provided with a drain pan 36, which is fixed in the tank 1 below the former to drain drippings from the operation of the condenser element 35.

A short conduit 37 establishes communication between the mixing chamber 22 and a flexible conduit 38. The latter is supported

in a suitable standard and is provided with some slack permitting of its jiggling action during the passage of air therethrough to prevent the adherence of any particles of fuel in the conduit 38 that would tend to impede the normal flow of fuel through the latter. The flexible conduit 38 serves as a conveyer from the device to the apparatus using the fuel.

In the operation of the present invention, the compressor 29 sucks its air supply from the interior of the tank 1. As the said air supply is dehydrated by the operation of the condenser element 35, the air supply will not only be uniform in its properties, but will also provide an air supply particularly adapted for establishing a most efficient fuel admixture.

After the air is compressed and stored in the reservoir 28, the same is first fed through the air motor 27 to drive the latter and in turn the brush 25 in the mixing chamber 22. As the air is exhausted from the air motor 27 it passes through the mixing chamber 22 gathering the particles of pulverized material being delivered by the operation of the brush 25, and forcing this admixture of air and pulverized material, constituting the fuel, through the conduit 37, conduit 38, and to the apparatus ultimately consuming the fuel. The air will not enter the tank 1 on its passage through the mixing chamber 22, as the brush 25 completely closes the passage opening 4, and the conduits 27' and 37 are longitudinally aligned to respectively expel and receive the air on its passage through the chamber 22.

It will, of course, be obvious that the regulation, adaptation, brush drive arrangement, and many other details of construction may be widely varied without departing from the spirit of the invention in providing an efficient carbureting apparatus for any desired purpose.

While the embodiment of the invention herein disclosed is intended for use in connection with a stationary installation, it is to be understood that the principle of the invention may be successfully embodied in constructions adaptable to internal combustion engines of motor vehicles, or for any other purposes. Further it is apparent that any suitable air suction element may be successfully employed for drawing the fuel from the mixing chamber 22, instead of the compressed air system as herein illustrated and described.

What I claim is:

1. In a pulverized fuel carbureting apparatus of the character described, a tank for storing the pulverized fuel, a mixing chamber disposed below and communicating with said tank, means for feeding said pulverized fuel from said tank to said mixing chamber, a condenser element mounted in said tank for dehydrating the fuel, a brush disposed horizontally in the mixing chamber, an air motor for driving the brush, an air conduit connecting the air motor with the mixing chamber, a flexible conduit connecting the mixing chamber with the apparatus using the fuel, and a condenser element mounted in the tank for dehydrating the air supplied to the air motor.

hydrating the air and pulverized fuel in said tank, a compressed air element drawing its air supply from said tank, and means for passing the compressed air through said mixing chamber for conveying the pulverized fuel from the latter.

5 2. In a pulverized fuel carbureting apparatus of the character described, a tank for storing the pulverized fuel, a mixing chamber disposed below and communicating with said tank, means for feeding said pulverized fuel from said tank to said mixing chamber, a condenser element mounted in said tank and operable for dehydrating the air and pulverized fuel in said tank, a compressed air element drawing its air supply from said tank, means for passing the compressed air through said mixing chamber for conveying the pulverized fuel from the latter, and an agitator 10 operatively supported in said tank.

15 3. In a pulverized fuel carbureting device, the combination of a tank for storing the pulverized fuel, a mixing chamber disposed below and communicating with said mixing chamber, means for regulating the flow of pulverized fuel from said tank to said mixing chamber, a removable screen mounted in said mixing chamber for screening the fuel on its passage from said tank to said mixing 20 chamber, a brush element rotatably mounted in said mixing chamber for feeding the fuel from said tank to said mixing chamber, a condenser element operatively mounted in said tank for dehydrating the air and fuel in the latter, a compressed air supply element 25 drawing its air supply from said tank, and an agitator operatively supported in said tank.

30 4. In combination, a pulverized fuel carbureting apparatus of the character described comprising a tank for storing the pulverized fuel, a supporting frame for said tank, a mixing chamber disposed below said tank, said tank provided with an opening communicating with said mixing chamber, means 35 for regulating the flow of the pulverized fuel from said tank to said mixing chamber, a removable screen member mounted in said mixing chamber for screening the pulverized fuel during its passage from said tank to said 40 mixing chamber, a cylindrical brush mounted for rotation in said mixing chamber and engaging the under side of said screen member for feeding the pulverized fuel from the said tank to the said mixing chamber, a condenser 45 element operatively mounted in said tank for dehydrating the air and pulverized fuel in said tank, a compressed air supply element drawing its air supply from said tank, an air motor driven by said air supply element 50 for operating said brush, a flexible fuel conduit for conveying the fuel from said mixing chamber, means for passing the compressed air through said mixing chamber for driving the fuel from the latter and through 55 said flexible conduit, means for regulating 60 65

said last mentioned means, and an agitator for the pulverized fuel suspended in said tank and longitudinally adjustable in the latter, and means for operating said agitator, said agitator being formed to automatically position and maintain itself on the top of the fuel supply in said tank by the rotation thereof.

70 In testimony whereof I affix my signature.
